UNITED STATES PATENT OFFICE

2,545,793

INTERNAL-COMBUSTION ENGINE OPERATING ON THE FOUR-STROKE CYCLE WITH COMPRESSION IGNITION

Harry Ralph Ricardo, London, England, assignor to Ricardo & Co. Engineers (1927) Limited, London, England, a company of Great Britain

Application June 22, 1948, Serial No. 34,417
In Great Britain June 23, 1947

3 Claims. (Cl. 123—32)

1

This invention relates to internal combustion engines operating on the four-stroke cycle with compression ignition, of the kind in which there is operatively associated with two power-producing cylinders (hereinafter called working cylinders) containing working pistons connected to the same crankshaft an air displacement cylinder (hereinafter called a pump cylinder) lying between the two working cylinders and containing a pump piston also connected to that crankshaft, the pump cylinder being provided with an inlet valve or valves for the admission of air thereto while the inlet valves of the working cylinders serve as the delivery valves of the pump cylinder, and the crank throw connected to the pump piston being displaced by 180° from the crank throws connected to the working pistons and the timing of the valves of the working cylinders being such that the power strokes of the working pistons occur alternately.

The object of the invention is to provide a satisfactory engine of the above kind operating with compression ignition.

In an internal combustion engine of the kind referred to operating with compression ignition according to the present invention, while the inlet and exhaust ports of the working cylinders are controlled, as in prior proposals, by poppet valves, the admission of air to the pump cylinder is controlled by a ported piston valve arranged to be reciprocated by suitable operating mechanism in a cylindrical valve housing having ports therein communicating with the pump cylinder and in a direction which is transverse and preferably at right angles to the plane containing the axes of the pump and working cylinders.

In any case each of the working cylinders preferably incorporate the features described in the specification of the present inventor's British Letters Patent No. 439,426 or in the specification of his British Letters Patent No. 457,491, the injection of fuel into the cylinder being effected for example as described in the present applicant's British Letters Patent No. 431,345.

The invention may be carried into practice in various ways but three alternative arrangements according to the invention are illustrated somewhat diagrammatically by way of example in the accompanying drawings in which,

Figure 1 is a sectional elevation of one form of engine according to the invention, the section being taken in the plane containing the axes of the three cylinders,

Figure 2 is a section on the line 2—2 of Figure 1, and

2

Figure 3 is a cross-section on an enlarged scale in a plane containing the axis of one of the working cylinders and lying at right angles to the plane in which the axes of the three cylinders lie.

In the construction illustrated the engine comprises a main casing A constituting the crank-case, in which a three throw crankshaft B is supported in bearings B¹, and a cylinder jacket 10 or housing in which are carried liners C, C¹, C² constituting the cylinders proper of the engine, these liners being of the kind known as "wet" liners.

Mounted upon the main casing A is a cylinder head unit D while at one end of the main casing A is a gear housing A¹ enclosing suitable transmission gearing, for example of the silent chain type, by which rotary movement is transmitted from the crankshaft B to a layshaft E 15 lying on one side of the engine and from which valve gearing is operated and to a fuel injection pump F on the other side of the engine. The crankshaft B, which carries a flywheel B² at one end has two throws B³ in the same angular position with a throw B⁴ situated between them and angularly displaced from them by 180°. Each of the throws B³ is connected by a connecting rod to a working piston G¹ in one of the outer two cylinders C and C¹ which constitute the working cylinders, while the throw B⁴ is connected by a connecting rod G² to a pump piston G³ in the central cylinder C² constituting the pump cylinder.

The dimensions of the crank throw B⁴ are such in relation to those of the similar crank throw B³ that the stroke of the pump piston G³ is greater than that of either of the two working pistons G¹. The bore of the pump cylinder C² is also greater than that of each of the working cylinders C and C¹, so that the displacement of the piston G³ or each stroke is thus greater than the displacement of each of the pistons G¹ in a ratio lying between 1.5 and 2.5.

Formed in the cylinder head unit D is a tubular housing D¹, the axis of which lies at right angles to the plane containing the axis of the cylinders C, C¹, C², this housing containing a liner D² which communicates with the interior of the cylinder C² through a series of ports D³ and contains a reciprocating hollow piston valve D⁴. The interior of the valve D⁴ is in communication with the atmosphere at one end through an inlet passage D⁵ so that the ports D³ constitute air inlet ports controlled by the piston valve. The piston valve D⁴ is operated by a rod D⁶ connected to one arm of a bell crank lever D⁷ piv-

oted at D⁸ the other arm of which is connected by a connecting rod D⁹ to an eccentric E¹ on the layshaft E.

The interior of the cylinder C² also communicates through delivery ports H controlled by poppet valves H¹ with the cylinders C and C¹, exhaust ports H² controlled by poppet valves H³ also communicating with this cylinder.

The poppet valves H¹ and H³ thus constitute the normal inlet and exhaust valves of each of the working cylinders C and C¹ and are operated in normal manner by rockers H⁴ which are pivoted to the cylinder head unit and acted upon by push rod and tappet mechanism H⁵, H⁶ from cams H⁷ on the layshaft E.

As will be seen from Figures 1 and 2 the arrangement is such that on its top dead centre the pump piston G³ approaches the cylinder head unit D as closely as mechanical considerations permit.

As will also be seen, from Figure 3, each of the cylinders C and C¹ is provided in the cylinder head unit with a combustion chamber J of the general type, described in the present applicant's British Letters Patent No. 439,426, communicating with its cylinder through a narrow passage J¹ in a heat insulated plug and provided with a seating J² for a fuel injection nozzle (not shown) to which fuel would be delivered appropriately by the fuel pump F.

The arrangement and operation of the piston valve D⁴ is such that during each suction stroke of the pump piston G³ air is drawn from the passage D⁵ while during each delivery stroke of the pump piston the ports D³ are closed. The valves H¹, H³ and the fuel injection pump F are operated so that the power strokes of the piston G¹ occur alternately, and one or other of the valves H¹ is open during each delivery stroke of the pump piston G³. It will thus be seen that the piston G³ delivers air alternately through the ports H and that the valves H¹ in addition to acting as the inlet valves of the working cylinders C and C¹ act alternately as the delivery valve for the pump piston G³.

What I claim as my invention and desire to secure by Letters Patent is:

1. An internal combustion engine operating on the four-stroke cycle with compression ignition including, in combination, a pair of similar working cylinders having inlet and exhaust ports, a pump cylinder disposed between and parallel to the working cylinders and communicating directly with the inlet ports of the working cylinders, working pistons and a pump piston respectively in the working cylinders and the pump cylinder, a common crank shaft to which the three pistons

are connected, the crank throw connected to the pump piston being displaced by 180° from the crank throws connected to the working pistons, and the volume displaced by one stroke of the

5 pump piston being greater than the volume displaced by one stroke of either of the working pistons in a ratio between 1.5:1 and 2.5:1, poppet valves controlling the inlet and exhaust ports of the working cylinders, a cam shaft driven from 10 said engine, connections between said cam shaft and said valves to drive the valves in such timed relation to the rotation of the crank shaft that the power strokes in the two working cylinders occur alternately, a cylindrical valve housing extending transversely across the upper end of the pump cylinder, communicating at one end with the atmosphere and having ports in its circumferential wall opening into the pump cylinder, a hollow ported piston valve disposed to reciprocate 15 within the valve housing and having ports therein which communicate with the ports in the valve housing twice during each complete cycle of operation of the said ported valve, and means rotating at half crank shaft speed for reciprocating 20 25 said ported valve so that it performs one complete cycle for each two revolutions of the crank shaft.

2. An internal combustion engine as claimed in claim 1 in which the means for reciprocating the piston valve comprises an eccentric carried by 30 the cam shaft, and linkage mechanism between said eccentric and valve to operate the latter.

3. An internal combustion engine as claimed in claim 2 in which the cam shaft extends along one side of the cylinders parallel to the crank shaft, 35 the operating mechanism for the poppet valves includes push rods and rockers, and the operating mechanism for the piston valve comprises a connecting rod the lower end of which engages an eccentric on the cam shaft, a lever having an approximately horizontal arm and an approximately vertical arm, means for connecting the approximately horizontal arm to the upper end of the connecting rod and means for connecting the approximately vertical arm to the reciprocating piston valve.

45 HARRY RALPH RICARDO.
